UNITED STATES PATENT OFFICE.

ROBERT N. CAUGHELL, OF SHEDD, OREGON.

SPOKE-EXTRACTOR.

SPECIFICATION forming part of Letters Patent No. 277,991, dated May 22, 1883.

Application filed February 24, 1883 (No model.)

To all whom it may concern:

Be it known that I, ROBERT N. CAUGHELL, of Shedd, county of Linn, State of Oregon, have invented an Improved Spoke-Extractor; and I hereby declare the following to be a full, clear, and exact description thereof.

My invention relates to a new and useful device for removing spokes from the hub; and it consists in a peculiar clamping-ring fitting to the spoke and acting as a lever, having a fulcrum on the hub, and a means for applying the power at the outer side, as will hereinafter fully appear.

The object of my invention is to remove spokes from the hub with facility and effectiveness.

Referring to the accompanying drawing, the figure is a view of my device, showing its application.

20 A represents the hub of a wheel, in which the spoke *a* is secured in the usual manner.

B represents a ring having oppositely-extending arms *b*. Through the sides of this ring fit set-screws *c*, on the ends of which are loosely fitted the clamping-jaws *C*. These jaws are preferably made with concave faces to better adapt them to fit the spoke. They are, as I have before said, loosely fitted on the set-screws, and this may be done in any suitable manner—as, for instance, by heading down the end of the screw on its face, and having a shoulder against its back, thus providing for the impingement of the screw against the jaw, and also for the movement of the ring after the jaws are clamped upon the spoke.

Pivoted to one arm *b* of ring *B* is a stout bar or rod, *D*, the end of which is curved to conform to the surface of the hub, against which it bears. In the other arm *b* is pivoted 40 a nut, *e*, through which a long screw, *E*, passes. The upper end of this screw is provided with a crank, *f*, and the lower end with a bearing, *g*, loosely fitted upon it. This bearing is curved to better fit the hub, and by reason of being fitted loosely upon the screw the latter may turn, while the bearing remains stationary against the hub.

In using the device the ring *B* is first clamped tightly to the spoke by means of the jaws *C*,

and the rod or bar *D* bears against the hub. 50 The screw *E* bears against it on the other side, and by operating the crank *f* the arm *b*, through which the screw *E* passes, is forced up, thus gradually changing the inclination of the ring *B*, which is in fact a lever, its fulcrum being against the hub through the bar *D*, and the spoke to which it is clamped being the weight. This change of inclination is possible because of the loosely-mounted jaws *C*, as explained, and as the change is effected 60 the spoke is drawn out from the hub. The pivoted nut *e* permits the operation of the screw *E* to be unaffected by the movement of the ring, so that the latter may change its inclination while the screw maintains its bearing. There is also an advantage in the pivoted nut, in that it allows the screw *E* to find the most desirable bearing upon the particular hub, and in all cases permits it to bear as close to the base of the spoke as possible, 70 whereby the best position may be obtained.

Having thus described my invention, what I claim as new, and desire to secure by Letters Patent, is—

1. In a spoke-extractor, the swinging ring 75 *B*, clamped to the spoke, the bar or rod *D*, bearing on the hub and acting as a fulcrum for the ring *C*, in combination with a means for applying power to the other side or end of the ring to move it on its fulcrum and draw 80 the spoke, substantially as herein described.

2. In a spoke-extractor, the ring *B*, having set-screws *c* and jaws *C*, loosely mounted thereon, whereby said ring may be clamped and pivoted upon the spoke, and the fulcrum bar or rod *D*, 85 pivoted to one side of the ring and bearing against the hub, in combination with means connected with the other side of the ring to move it upon its fulcrum, substantially as and for the purpose herein described.

3. A spoke-extractor consisting of the ring *B*, pivoted and clamped upon the spoke, the fulcrum-rod *D*, pivoted to the ring on one side and bearing against the hub, and the operating-screw *E*, pivoted to the ring on the other 95 side and bearing against the hub, substantially as herein described.

4. A spoke-extractor consisting of the ring

B, having the side arms, *b*, the set-screws *c*, and jaws *C*, loosely fitted on said screws, whereby said ring may be clamped and pivoted upon the spoke, the fulcrum-rod *D*, pivoted to one arm *b* and bearing against the hub, the pivoted nut *e* in the other arm *b*, and the operating-screw *E*, passing through said nut

and bearing upon the hub, substantially as herein described.

In witness whereof I hereunto set my hand. to
ROBERT N. CAUGHELL.
